UNITED STATES PATENT OFFICE.

JOSEPH KATCHER, OF MADERA, PENNSYLVANIA.

RAIL-JOINT.

1,382,511.

Specification of Letters Patent. Patented June 21, 1921.

Application filed March 21, 1921. Serial No. 454,140.

To all whom it may concern:

Be it known that I, JOSEPH KATCHER, a citizen of the United States, residing at Madera, in the county of Clearfield and State of Pennsylvania, have invented new and useful Improvements in Rail-Joints, of which the following is a specification.

My present invention has reference to an improved means for connecting the confronting ends of railway rails.

A primary object is to produce a rail joint in which the rails are connected in a manner to hold the same against lateral, tilting or vertical movement and to permit only such longitudinal movement as required in the expansion and contraction of the rails, without the employment of bolts and nuts or similar devices that are liable to disassociation by the pounding of the rolling stock on the rails.

Another important object is to produce a rail joint that will establish an electric bond, and wherein the means holding the rails connected may be arranged thereon after the rails have been brought into confronting engagement, and likewise removed therefrom without necessitating the movement of the rails away from each other.

A still further object is to produce in a rail joint, fish plates that have lugs on their inner faces which are received through the bolt openings in the webs of the rails, said plates having their outer faces provided with longitudinal wedge ribs, while arranged on the bottom of the rails and having its base in contacting engagement with the confronting ends of the rails, is a yoke, the arms of the yoke having hooks one of which being designed to overlie and contact with the rib on one of the plates, the other hook being engaged by a wedge key received in a suitable depression in the second plate, the said wedge key overlying and in contacting engagement with the rib on the said second plate, while means is provided for locking the wedge key and yoke associated to hold the latter against movement in any direction.

The foregoing, and other objects which will appear as the nature of the invention is better understood, may be accomplished by a construction, combination and operative association of parts, such as is disclosed by the

drawings which accompany and which form part of this application.

In the drawings:

Figure 1 is a side elevation of two rails connected in accordance with this invention.

Fig. 2 is a similar view but looking toward the opposite side of the rails.

Fig. 3 is a top plan view.

Fig. 4 is a horizontal sectional view on the line 4—4 of Fig. 1.

Fig. 5 is a transverse sectional view on the line 5—5 of Fig. 4.

Fig. 6 is a similar sectional view on the line 6—6 of Fig. 4.

Fig. 7 is a sectional view approximately on the line 7—7 of Fig. 4, but showing the yoke moved off of the ribs of the fish plates and the manner in which the same may be canted on the rail to arrange the yoke for engagement with the fish plates, or to permit of the removal of the said yoke.

Fig. 8 is a perspective view looking toward the outer face of one of the fish plates.

Fig. 9 is a similar view looking toward the inner face of one of the fish plates.

Fig. 10 is a perspective view looking toward the outer face of the second fish plate.

Fig. 11 is a similar view looking toward the inner face of the said fish plate.

Fig. 12 is a perspective view of the wedge key.

Referring now to the drawings in detail, the numeral 1 designates the confronting ends of two railway rails. The rails have their webs provided with the usual bolt openings.

My improved joint contemplates the provision of two fish plates which are indicated by the numerals 2 and 3 respectively. Each fish plate has its inner face provided with projecting lugs 4 and round openings providing pockets 5 between the lugs. The lugs 4 of the fish plates are designed to be passed through the bolt openings in the webs of the rails, and the lugs on one of the fish plates are designed to be received in the openings or pockets 5 of the adjacent fish plates. The bolt openings in the rails are elongated to permit of the proper expansion and contraction of the rails without influencing the joint provided by the fish plates. Two of the lugs, on the fish plate 2 are surrounded by copper sleeves 6, and embedded in a suit-

able channel on the inner face of the said fish plate there is a conductor wire 7 that is connected to the copper sleeves 6. The copper sleeves are compressed between the longitudinal walls of the openings in the webs of the rails through which they are received, and also the conductors 7 project a suitable distance beyond the inner face of the plate 2 to insure a proper contacting engagement thereof with the webs of the respective rails 1. Thus an electric bond is established between the rails which is not interfered with by the expansion and contraction of the rails.

Both fish plates have their body portions of a thickness approximately equaling the distance between the sides of the heads of the rails and the webs thereof. The fish plates have on their outer straight faces, at the center thereof, longitudinally extending ribs 8 and 9 respectively. These ribs project outwardly from the lower angle edges of the fish plates. The outer face of each of the ribs is arranged at an upward inclination, as indicated by the numeral 10, and each rib is wedge shaped, that is the same is gradually decreased in thickness from one to its opposite end. The upper or top surface of each of the ribs 8 and 9 is flat, as at 11, and the outer face of the fish plate 2, in a line with the said upper surface 11 of the rib 10 thereon is provided with a longitudinal groove 12. The inner wall of this groove is inclined, as at 13, and the said groove is gradually decreased in depth from one end thereof to the other end, the inclination being arranged opposite to the inclined or beveled outer surface of the ribs.

The numeral 14 designates a yoke member. The yoke has its base 15 provided with a flat upper surface 16, and the arms 17 and 18 of the yoke have their inner surfaces arranged at an upward inclination, as at 19 respectively and are beveled from one of their sides to their opposite sides, to conform to the beveled or wedge surfaces 9 and 10 of the ribs 8 on the respective fish plates with which the arms of the yoke engage. Each arm, 17 and 18 has at its upper portion an inwardly directed projection providing a jaw. The jaw on the arm 17 is indicated by the numeral 20, and that on the arm 18 by the numeral 21. The jaw 21 is formed by cutting the inner face of the arm 18 at an outward inclination, as indicated by the numeral 22, providing the said arm with a flat shoulder 23 below the jaw 21. As disclosed in Fig. 7 of the drawings the yoke is of a size and construction to permit of the same being canted and arranged on the base of the rail outward of the fish plates, so that the fish plates may be properly positioned on the rail ends before the yoke is moved thereover. The yoke, when arranged

on the fish plates will have the inclined and beveled inner surfaces 19 of their arms 17 and 18 contacting with the beveled surfaces of the ribs of the respective fish plates, and when in proper position, the straight upper surface 16 of the base 15 of the yoke will be disposed centrally of the meeting ends of the rails. The jaw 21 is projected a suitable distance above the rib 10, and forced into the wedge slot 12 in the fish plate 2 and against the inclined face 22 of the jaw 21 is a wedge key 24. The wedge key has its reduced end provided with spaced apertures 25 and when forced into tight engagement between the walls of the groove, and the jaw 21 an element, such as a cotter pin 26 is inserted through one of the openings 25. Preferably, one of the legs of the cotter pin is bent against one of the sides of the arm 18, as disclosed in Fig. 6 of the drawings which will assist in holding the yoke against movement.

The rails are supported on the usual ties, the ties, adjacent to the confronting ends of the rails being positioned a suitable distance from the joint. The fish plates are applied to the opposite sides of the rails. The yoke is then arranged beneath the rails, first in the canted position illustrated in Fig. 7 of the drawings, outward of the ribs 8 and 9. The yoke is then moved upwardly so that the surface 16 thereof is brought against the flat base of the rails, and the yoke is moved in the direction of the ribs so that the inclined inner edges of its arms 17 and 18 will be in frictional engagement with the outer beveled and inclined edges of the ribs 8 and 9. The yoke is moved along the ribs until the said yoke is disposed approximately centrally with respect to the meeting ends of the rails. The jaw 20 is now arranged over the flat upper surface 11 of the rib 9 on the fish plate 3, and the jaw 21 is brought opposite the groove 12 in the fish plate 2. The wedge key 24 is now inserted between the wall of the groove 12 and the inner inclined wall of the jaw 21, and when wedged between these walls the cotter pin 26 is inserted through one of the openings 25 in the wedge, and the rails are connected in a comparatively simple but thoroughly effective manner.

Having described the invention, I claim:

1. In combination with the confronting ends of rails having bolt openings through their webs, of fish plates on the sides of the rails, lugs on the fish plates passing through the openings in the rails, a wedge rib on the outer face of each plate, a yoke having jaw portions one of which is arranged over the wedge rib of one plate, a wedge key arranged over the rib of the second plate and received in the second jaw of the yoke.

2. In combination with the confronting

ends of rails having bolt openings through their webs, of fish plates on the sides of the rails, lugs on the fish plates passing through the openings in the rails, a wedge rib on 5 the outer face of each plate, a yoke having jaw portions one of which is arranged over the wedge rib of one plate, a wedge key arranged over the rib of the second plate and received in the second jaw of the yoke, and 10 removable means sustaining the wedge key in such engagement.

3. In combination with the confronting ends of rails having bolt openings through their webs, of fish plates on the sides of 15 the rails, lugs on the fish plates passing through the openings in the rails, a wedge rib on the outer face of each plate, a yoke having its arms arranged at an inclination and beveled from one to the opposite edge 20 thereof and having jaws at their outer ends, said yoke designed to be moved over the plates to cause the inclined surfaces of their arms to engage with the wedge surfaces of the ribs and to arrange the base of the 25 yoke beneath the confronting ends of the rails, one of said jaws overlying and in contacting engagement with the upper surface of the rib of one of the plates, and a wedge key disposed over the rib of the second

plate, in engagement with the jaw of the 30 second arm of the plate, and means holding said wedge key in such engagement.

4. In combination with the confronting ends of rails having bolt openings through their webs, of fish plates on the sides of the 35 rails, lugs on the fish plates passing through the openings in the rails, a wedge rib on the outer face of each plate, one of said plates having a wedge slot in the plane of the upper wall of the rib thereon, a yoke having 40 inclined arms provided with angular confronting faces and jaws at the outer ends thereof, designed to be forced over the rails and fish plates to bring the under face of the yoke in a line with the confronting ends 45 of the rails and in contact therewith, the arms of the yoke in engagement with the wedge faces of the ribs, one of the jaws in contacting engagement with the upper face of one of the ribs, and the opposite jaw 50 above the rib on the opposite fish plate, and a wedge key inserted in the wedge slot in the last mentioned fish plate and received in the jaw of the yoke adjacent thereto, and removable means holding the wedge key in 55 such engagement.

In testimony whereof I affix my signature.

JOSEPH KATCHER.
